UNITED STATES PATENT OFFICE.

DANIEL E. KILROY AND WILLIAM A. BRADEN, OF CHICAGO, ILLINOIS.

SIGNAL SYSTEM FOR ELEVATORS.

1,180,300.

Specification of Letters Patent. Patented Apr. 25, 1916.

Application filed June 25, 1908. Serial No. 440,353.

To all whom it may concern:

Be it known that we, DANIEL E. KILROY and WILLIAM A. BRADEN, citizens of the United States, residing at Chicago, in the county of Cook and State of Illinois, have invented certain new and useful Improvements in Signal Systems for Elevators, of which the following is a specification.

In the operation of signal systems for elevators as at present installed, when the person desiring to become a passenger in a car manipulates the annunciator or signal button a lantern is lighted in the car and another lantern is lighted adjacent the elevator shaft of the floor where the passenger stands as the car approaches the floor where the system was actuated by such prospective passenger, in order to notify the elevator conductor to stop the car at such floor, and to apprise the passenger of the approach of the car. As these systems are at present constructed they are so arranged that when the car is full and cannot receive more passengers the elevator operator by pushing a button can transfer any signals that may have been set on other floors to be passed by his car to the following car but no means known to us have heretofore been provided in a signal system employing current of a relatively high voltage for the signal displaying circuit and current of a relatively low voltage for the signal actuating circuit, or in signal systems wherein relays using low voltage current are utilized for the purpose of controlling higher voltage circuits, or wherein a low voltage circuit only needs be interrupted in the elevator car in order to obliterate the signals which may have been set in advance of the movement of the car until at or after the time the car passes or has passed the floors where such last mentioned signals have been set.

The principal object of the present invention is the provision of an arrangement of apparatus and electrical circuits so constructed that the elevator operator can at any time obliterate all signals which the movement of his car would otherwise give, in order that false signals may not be given to awaiting passengers.

A further object of this invention is to provide such an arrangement of parts that the signal system for any elevator car, or

any one car in a bank of elevator cars, may be thrown out of circuit, or restored, as may be desired, at the will of the elevator conductor or starter, or automatically so far as the car operator is concerned, for express service, with facility and without the need of permanent disarrangement of the signal system, and one which will be operable from a moving car or from any desired location.

In carrying out our invention we have provided the construction illustrated in the accompanying drawings, wherein,

Figure 1 is a diagrammatic illustration of an elevator signal system embodying our improvements, Fig. 1^a is a simplified diagram view illustrative of the circuits employed in exhibiting and controlling the signals in connection with one of the intermediate floors; Fig. 2 is a perspective view of the moving brush carrier and other parts adapted to cooperate with the contact members illustrated diagrammatically in the upper right hand corner of Fig. 1, Fig. 2^a is a somewhat diagrammatic longitudinal vertical sectional view of the device of Fig. 2; Fig. 2^b is a vertical section of Fig. 2 taken on the line 2^b—2^b; Fig. 2^c is a perspective diagrammatic figure showing the means for oscillating the contact carrier. Fig. 3 is an enlarged detail elevation of the magnet coils, armatures, connections, and mercury pots illustrated at the left of Fig. 1, Fig. 4 is an enlarged detail of the circuit changer as illustrated at 4 in Fig. 1, Fig. 5 is a plan view of the circuit changer illustrated in Fig. 4, Fig. 6 is a section of the switch illustrated at 13 in Fig. 1, showing said switch in open position, Fig. 7 is the switch of Fig. 6 shown in closed position, and Fig. 8 is a diagrammatic illustration of a modified form of the present invention.

Referring to Fig. 1 of the drawing, 11 denotes one of a series of elevator cars arranged with the usual shafts in such a manner that they will pass up and down such shafts through the several floors of the building. Each such car is provided with a signal lamp, 12, and a signal operating switch, 13, which is provided in order that the elevator operator may transfer the stopping signal to the next car in the event that he does not wish to stop to take on the passenger, or may interrupt the signal system so that the movement of the car operated by him will

give no further signals, or that he may restore the signal system to its normal operative condition, all as will hereinbelow more fully appear. Adjacent to the elevator shaft on each floor there is provided a signal button, for example, 156, by which the person who wishes to become a passenger in the next elevator is enabled to close a normally open electrical circuit and thereby actuate the signal mechanism in such a manner that as a car approaches the floor where the signal has been given the signal lantern in the car will be lighted, signaling the operator to stop the car at such floor, and the signal adjacent to the elevator shaft of such floor will also be lighted, in order to inform the prospective passenger and the elevator conductor respectively. The signal buttons on the top and bottom floors are single as the car moves in but one direction from such floor, whereas a double set of buttons is provided at all intermediate floors in order that signals may be given for cars going up or down as the case may be. Single signal lanterns are likewise provided on the bottom and top floors and double signal lanterns on the intermediate floors for the same reason.

In the form of the present invention as illustrated in the accompanying drawings there has been shown but a single elevator, though it is, of course, obvious that the present apparatus is applicable by mere extension to any number of elevators, and furthermore that one set of push buttons is sufficient to enable one to actuate the entire signal system.

If a person on any floor of the building desires to signal the elevator car he operates one or the other of the push buttons according to the direction in which he wishes to travel, pushing the upper button if he wishes to go up or the lower button if he wishes to go down, thereby permitting the commutator mechanism in Fig. 2 to actuate the signal system. This commutator mechanism is usually driven by means of a chain A which drives a sprocket B loosely carried on the worm shaft 15. The chain passes over a sprocket 270 on the shaft 271 which carries the main sheave 272 around which pass the elevator ropes. The shaft 271 is supported by the usual bearings 273. In view of this connection between the overhead sheave shaft of the elevator car the shaft 15 will move according to the movement of the car, suitable shifting mechanism comprising a tail piece c traveling in guides d, e and controlled by springs d', e', being provided at each end of the shaft 15, alternately opening and closing the up and down sets of contacts, so that the "up" car signal circuits will not be closed when a "down" push button has been pressed and vice versa. The shaft 15 is journaled at each of its ends

as indicated at f and carries between them the brush carrier mechanism 16, which in turn carries a plurality of contact members, below to be described, arranged to contact with the contact strips and plates also hereinafter to be described in a manner there stated. Assuming that the tail piece c is moving in the direction indicated by the arrow (Fig. 2^c) in the guide d, when it passes the spring d', and the shaft 15 reverses its movement, the tail piece c will be moved into the guide e, and since the carrier mechanism is pivoted at g, such movement will shift the carrier mechanism 16 from the position shown in Fig. 2^b which shows the contacts made for the "down" movement of the car, and by the movement of the rocker arms 16', 16' will move the carrier mechanism 16 into a corresponding position for the operation of the "up" signals.

We show the traveling brush carrier mechanism in Fig. 2 in operative contact with the contact plates which are in circuit when the car is traveling upward, and it is apparent that such position will allow the lighting of no "down signal" lamps, since one pair of the "down" brushes contacts with the plate 46, another pair with the plate 239' and a third series with the plate 96, only; no communication being established between any of the several plates referred to with others thereof or with the plate 161, as is requisite for the operation of the "down" signal.

The power for operating the signal system may be obtained from any convenient source of electricity, and the circuit wires a, and b, are preferably led to a switch-board, 17, provided with a suitable starting switch 18, for the shunt field below mentioned. From the contact, 19, electrical connections are led to the brush, 20, and from the contact, 21, to the brush, 22, and from the contact, 23, to the contact, 24, which is connected to the shunt field on the transformer, 25, which carries on the commercial high voltage side (ordinarily 110 volts) the said contacts, 20, 22, and 24. At the other side of the transformer there is produced current of a low voltage, say ten volts, for the operation of the push buttons and parts connected therewith, below described. From one brush on the ten volt side of the transformer a wire, 26, feeds one side of each of the push buttons, 125, 126, 127, 128, and 129, and 155, 156, 157 and 158. A branch from this wire, 28, leads to a contact, 29, on the three point switch, 30. From the other brush on the ten volt side of the transformer a wire, 31, leads to the series of armatures, 213, 213', below described in connection with Fig. 3. From the wire, 31, a branch leads to a coil on the circuit changing device 33, shown more in detail in Figs. 4 and 5. From the adjacent coil on the circuit changing device, 139

33, a wire, 34, leads to one side of the push button, 13, and the opposite side of the push button, 13, is connected to the contact, 35, on the switch, 30, by the wire, 36. From the 5 wire, 34, a branch 37 leads to one 62' (in the particular circuit illustrated) of the dead contacts on the series of contacts, 39', the alternate ones of which series are connected to the down set back wires for a purpose 10 to be hereinafter described. The contact, 35, is connected by the wire, 41, to the contact, 39, on the circuit changer, 33, and the contact, 39, is in turn connected to the contact, 42, by the wire, 43. The contact, 44 15 (see Fig. 4) is connected to the transfer button return plates, 45 and 46, by the wires, 47 and 48. The contact, 49, is connected to the contact, 50, on the switch, 30, by the wire, 51, and the contact, 52, is connected to one 20 side of all of the lanterns, 170, 171, 172, 173, and 185, 186, 187, 188, and 189, by the wire 55, and branches leading therefrom, and the car light, 12. The contact, 56, is connected to the contacts, 57 and 58, by the 25 wire, 59, and a branch 60 leading therefrom, respectively. A branch, 61, may be led from the wire, 59, to the contact, 62, a switch, 63, placed in circuit therewith, for use when it is desired to run the car express to a certain 30 floor. From the contact, 64, of the switch 30 (Fig. 1) a wire, 65, leads to the contact, 66, and the contact, 67. From the contact, 68, connection is made by the wire, 69, to the contact, 70, on the main circuit switch, 71. 35 From the contact, 72, connection is made by the wires, 73 and 74, to the contact, 75, on the said switch, 71, and by the wire, 76, to the series of mercury pots, 211', and by the wire, 78, to the series of mercury pots, 211. 40 These mercury pots, 211, are in turn connected by wires, 80, 80', 80², 80³, 80⁴, etc., respectively to the contacts, 85, 86, 87, 88, 89, and the mercury pots 211' are in turn connected by wires 90, 90', 90², 90³, 90⁴, respectively, to the contacts, 95, 96, 97, 98, 99, etc. 45 The contacts, 100, 101, 102, 103, 104, etc., are connected by the wires, 105, 106, 107, 108, and 109 to their down set back plates, 110, 111, 112, 113, 114, respectively. The contacts 130, 131, 132, 133 and 134 are connected by wires, 135, 136, 137, 138 and 139 to the up set back plates, 140, 141, 142, 143 and 144. The contacts, 115, 116, 117, 118, are connected by the wires, 120, 121, 122, 123, to the 50 down push buttons, 155, 156, 157, and 158, respectively. The contacts, 145, 146, 147, 148, 149 are connected by the wires, 150, 151, 152, 153, 154, to the up push buttons, 129, 128, 127, 126 and 125. From the contacts, 55 160, 161, 162, 163, wires, 165, 166, 167, 168, respectively, lead to the lanterns, 170, 171, 172, 173. The contacts, 175, 176, 177, 178, 179, are connected by the wires, 180, 181, 182, 183, 184, to the lanterns, 185, 186, 187, 188, 60 189.

Referring to Fig. 3 of the drawings, it will be noted that the upper binding post of the mechanism for controlling the down signals, the same being shown in the lower part of said Fig. 3, for example the post 70 116, carries a wire 201 which is connected to the release magnet coil 202, the other end of which coil is connected to the binding post 203. The lower binding post, for example, 101, carries a wire, 205, connected 75 to the reset magnet coil 206, the other end of which coil 206 is likewise connected to the binding post 203 by a wire 207. The binding post 203 is also connected to the wire 31 by a wire 208. The armature 209, 80 is pivoted adjacent the coil, 206, in such a manner that when said coil is energized, the armature is lifted and the needle, 210, raised out of the mercury in the pot, 211, which mercury pot, 211, is in turn connected 85 to the contact, 72, by the wires 76 and 78. (See Fig. 1.) The said armature, 209, is so arranged that when its left hand end is depressed by the energization of the coil, 206, the armature, 213, will pass above the 90 upturned end, 214, and engage therewith. The said armature, 213, is so arranged with relation to the coil, 202, that when said coil is energized, the armature, 213, will release the armature, 209, and allow the contact 95 needle, 210, to drop into the mercury in the pot, 211, and thus restore the electrical connection.

Referring to Figs. 6 and 7 wherein are illustrated details of the preferred form of push button, it is to be noted that when the button 230 is pushed inwardly, the lever 231 which is pivoted at 232 will depress the contact bar 235 and close the circuit between contacts 236^a and 237^a. The contact bar 235 is connected to the lever 231 at a point 233 by means of a connection having sufficient play to allow the contact bar to come in contact with both contacts 236^a and 237^a. 105 110 115 120 125 130

Fig. 4 illustrates the improved form of positive action circuit breaker, where it will be noted that there is provided a pair of magnet coils, 216 and 217, so arranged in series that when they are energized the armature, 218, will move in the direction indicated by the arrow and by means of the pawl, 219, engaging with the ratchet wheel, 220, move the sprocket, 221, such a distance that one of the teeth thereof will depress the contact bar, 222, pivoted at 223 and ride upon the boss 212 so that connection will be established by the connected contacts, 224 and 225, between the contacts, 42 and 56, and so that the connection which the contacts, 49 and 52, and the contacts, 39 and 44, have by the connected contacts, 226 and 227 and 228 and 229, respectively, will be interrupted. It is to be noted that a momentary energization of the coils, 216 and 217, 130 135 140 145 150 155 160 165 170 175 180 185 190

is sufficient to interrupt the circuits as just stated, since when one of the teeth 221^a rides onto the boss 212 it remains there until the magnet is again energized, and that to restore such circuits it is necessary that the coils, 216 and 217, be again energized, when the tooth 221^a last referred to will descend from the boss 212.

Referring to Fig. 8, it will be noted that the circuits are the same as in Fig. 1 with the following exceptions: The wire, 51, leads directly from the contact, 50, to the contact 236^b acting in conjunction with contact 237^b, without the intervention of the circuit changer, 33. The wires, 43, 59 and 60, and the circuit changer, 33, and the various connections shown in Figs. 4 and 5, are eliminated.

Referring to Fig. 2 of the drawings, it is to be noted that when the elevator car is descending the traveling brush carrier mechanism or commutator illustrated in this figure and the contacts carried thereby bear relation to the contacts illustrated in Fig. 1, illustrated as to the upper contacts in full line and lower contacts in dotted lines as will hereinafter more fully appear.

The operation of our invention is as follows: Referring to Fig. 1^a, it will be noted that when, for example, a passenger standing at the third floor pushes the button 156, the low voltage circuit for setting the mechanism is established from the low voltage side of the transformer 25 through conductor 31, binding post 203, magnet 202, binding post 117, conductor 121, push button 156, common feed wire 26, signal 251, back to the transformer 25. This circuit energizes the magnet 202, causing the attraction of the armature 213 which allows the needle 210 to fall into the mercury pot 211, so that as the descending elevator approaches such floor, the traveling commutator 16 moving conformably with the elevator and carrying the contacts 237 and 238 (Figs. 2 and 2^b) will establish a circuit between the contacts 86 and 177; and the high voltage lighting circuit is then completed as follows: conductor *a*, switch contact 70 on switch 71; conductor 69, contact 68 on the switch 30, contact 50, conductor 51, through the contacts 49, 52, conductor 55, through the lamp 187, conductor 182, contacts 177 and 86 (which have been bridged by the contacts 237 and 238 on the traveling commutator of Figs. 2 and 2^b), conductor 80', needle 210, mercury pot 211, conductors 78, 76, 74, contact 75 on the switch 71, through said switch 71 to conductor *b*, thus completing the circuit. This will cause the lighting of the floor lantern 187, and of the car lamp 12, the circuit for which latter is as follows: conductor *a*, switch contact 70 on switch 71, conductor 69, contact 68 on the switch 30, contact 50, conductor 51, through

the contacts 49, 52, conductor 55, conductor 53, through the lamp 12, contact plate 239, brushes 240 and 241, contact 86, conductor 80', needle 210, mercury pot 211, conductor 76, conductor 74, contact 75 on the switch 70, to conductor *b*, thus completing said car lamp lighting circuit. As the car passes the floor on which the passenger stands, the brush contacts 237 and 238 contact with a dead plate 85 which interrupts the circuits heretofore described, and a circuit will then be established as follows: from the low voltage side of the transformer, 25, conductor 31, conductor 208, binding post 203, conductor 207, magnet 206, conductor 205, binding post 201, conductor 106, contact 111, through the brush contacts 242, 243, contact plate 45, conductor 47, contacts 44, 39, conductor 41, contact 35 on switch 30, conductor 26, to the opposite side of the transformer 25. This circuit energizes the magnet 206 which attracts its armature 214, withdrawing the needle 210 from the mercury pot 211 and the armature 209 which is thereby prevented from again dropping the needle upon the deenergization of the magnet 206 by means of the armature 213 of the magnet 202 which overlies one end 214 of the armature 209 (when the magnet 202 is deenergized,) and thus mechanically holds the contact 210 out of contact with the mercury in the pot 211. If, however, the elevator conductor does not wish to stop at the floor where the signal has been given, by pushing the button, 13, and thereby establishing a circuit through the coils, 216 and 217, and the consequent movement of the armature, 218, as described in connection with Figs. 4 and 5, he can extinguish all the floor lanterns below him, and also the car light, by reason of the fact that the flow of current through the wires, 51, 53 and 55, will be interrupted by the movement of the contacts, 226 and 227, but low potential current will continue to flow through the wires, 43 and 59, to the contact plate, 57, in order that as the car approaches the bottom floor the circuit changer 33 will assume its normal position shown in Fig. 4 restoring the circuit so that the lamp may be lighted—that is to say the traveling commutator 16 carrying the brush contacts 242, 243, will bridge the contact plates 45 and 57', establishing a circuit as follows: from transformer 25, through conductor 31, magnets 217, 216, conductor 34, to contact plate 57', contact plate 45, conductor 47, contacts 44, 39, conductor 41, contact 35 on switch 30, conductor 26, to the opposite pole of the transformer. This circuit will energize the magnets 216—217, causing the attraction of the armature 218, causing the toothed sprocket 221 to ride off from the boss 212, and allow the circuit changer 4 to attain its normal condition shown in Fig. 4.

The operation of the device shown in Fig. 8 is the same as that of Fig. 1, with the following exceptions: The pushing in of the push button, 230, interrupts the common feed of all of the lanterns and the car light feed for such a period of time as such button is so depressed, and likewise interrupts the common feed for the set back plates, 45, 46 (Fig. 1). It is to be noted that the push button, 230, is so arranged that when it is depressed it may be held in such position against the pressure of the spring, 255, by giving the button, 230, a slight turn, as indicated in Fig. 6.

At 250 is illustrated a switch which may be used as a short circuit around an annunciation bell, 251, when it is not desired to have the bell ring when the push buttons are manipulated.

While the present system has been described as applicable to a single car, it is obviously capable of adaptation to the usual series of elevators by mere extension in the customary manner as above stated, and it is also to be noted that many other ways of interrupting and restoring the circuits for the purpose above described, may be designed without departure from the spirit of the present invention and are therefore intended to be comprised within the terms of the appended claims.

Having thus described our invention and illustrated its use, what we claim as new and desire to secure by Letters Patent is the following:—

1. An electric elevator system comprising, in combination, a relatively high potential lamp circuit, means operated by relatively low potential current for closing the lamp circuit, automatic means operated by low potential current for restoring said circuit closing means to open circuit position, auxiliary means operable from the car for breaking both the lamp circuit and the circuit through said restoring means.

2. An electric elevator signal system comprising, in combination, a relatively high potential lamp circuit and a relatively low potential controlling circuit, including three parallel branch circuits comprising, respectively, a manually operated lamp circuit closing device adjacent the elevator shaft, a resetting device for said lamp circuit closing device controlled by contacts operated by the movement of the car, and auxiliary lamp circuit breaking means operable from the car and adapted to open and close the circuit through said resetting device.

3. An electric elevator signal system comprising, in combination, a plurality of relatively high potential lamp circuits for each floor, lamp circuit closing devices operated by relatively low potential for each floor connected in parallel with a manually operated circuit closing device on that floor, and

separate circuit breaking means for each lamp circuit on that floor whereby the lighting of a lamp can be avoided when desired.

4. An electric elevator signal system comprising, in combination, a relatively high potential lamp circuit, a relatively low potential controlling circuit for closing a section of said lamp circuit, contacts operated by the movement of the car for completing the lamp circuit and a relatively low potential lamp circuit breaking device operable from the car.

5. An electric elevator signal system comprising, in combination, a lamp circuit, a manually controlled lamp circuit opening device, and separate automatic means for restoring said lamp circuit opening device to circuit closing position at a predetermined point in the travel of the car.

6. An electric elevator signal system comprising, in combination, a lamp circuit, a manually operated lamp circuit closing device, means for restoring said last-mentioned device to open circuit position after operation, and auxiliary means operable from the car for breaking the lamp circuit and preventing the action of said restoring means, and separate means for automatically returning said auxiliary means to their original position at a predetermined point in the travel of the car.

7. An electric elevator signal system comprising, in combination, a relatively high potential lamp circuit comprising lamps on each floor and a lamp in the car and relatively low potential controlling circuits therefor, including lamp circuit closing devices, means for restoring said devices to open circuit position after operation and means operable from each car adapted to break the high potential circuit for the lamp on the car and the lamps on each floor corresponding therewith, said last-mentioned means being also adapted to break the circuit through the said restoring means.

8. An electric elevator signal system comprising, in combination, a relatively high potential lamp circuit comprising a lamp adjacent the elevator shaft and a manually operated circuit closing device adjacent the elevator shaft operated by relatively low potential, a contact device moving in synchronism with the car, a manually operated circuit closing device on the car and three circuit opening and closing devices in series in the circuit of said lamp adapted to be closed, respectively, by the operation of said first-mentioned circuit closing device, by said contact device and by said circuit closing device on the car, and the first two adapted to be opened by the said contact device and the third by the said circuit closing device on the car.

9. An electric elevator signal system comprising, in combination, a lamp circuit,

push button adjacent the elevator shaft, a contact device moving in synchronism with the car and a manually operated switch on the car, a circuit for controlling said lamp circuit having three parallel branches adapted to be opened and closed, respectively, by said push button, by said contact device and by said manually operated switch, and circuit opening and closing devices in the second branch circuit controlled by the passage of current through the third branch circuit.

10. An electric elevator signal system comprising, in combination, a lamp adjacent the elevator shaft, automatic means for completing a section of the circuit for said lamp when the car approaches the floor where the said lamp is located, auxiliary means on the car adapted to break said lamp circuit, and means operated by the movement of the car for restoring the connection broken by said auxiliary means at a predetermined point in the travel of the car.

11. An electric elevator signal system comprising, in combination, a relatively high potential lamp circuit, means controlled by a circuit closing device adjacent the elevator shaft for closing the lamp circuit when the car approaches that floor, a relatively low potential circuit including a device adapted

to open the said lamp circuit and a circuit opening and closing device for said last-mentioned circuit arranged on the car.

12. An electric elevator signal system comprising, in combination, a lamp circuit, a controlling mechanism therefor including an intermittently rotatable member, a circuit make and break device operated thereby and arranged in series with said lamp circuit, and electromagnetic means for imparting 40 rotary motion to said member.

13. An electric elevator signal system comprising, in combination, a lamp circuit, a controlling mechanism therefor including an intermittently rotatable member, a circuit 45 make and break device operated thereby and arranged in series with said lamp circuit, and means for imparting rotary motion to said member.

In testimony whereof we have hereunto 50 signed our names in the presence of two subscribing witnesses.

DANIEL E. KILROY.
WM. A. BRADEN.

Witnesses as to Daniel E. Kilroy:

PAUL CARPENTER,
RALPH W. HICKS.

Witnesses as to William A. Braden:

PAUL CARPENTER,
ALFRED Y. ANDREWS.
